BARTON H. JENKS, OF BRIDESBURG, PENNSYLVANIA.

Letters Patent No. 92,612, dated July 13, 1869.

IMPROVEMENT IN SHUTTLE-BOX-OPERATING LEVER FOR LOOMS.

The Schedule referred to in these Letters Patent and making part of the same.

To all whom it may concern:

Be it known that I, BARTON H. JENKS, of Bridesburg, in the county of Philadelphia, and State of Pennsylvania, have invented a new and useful Improvement in Box-Levers for Looms; and I do hereby declare that the following is a full, clear, and exact description thereof, reference being had to the accompanying drawings, making part of this specification, in which—

Figure 1 is an elevation of one side of a loom-frame, showing my improved box-lever applied to a shuttle-box rod.

Figure 2 is a top view of fig. 1.

Figure 3 is a similar view of the same parts shown in fig. 1, representing the position which the loaded arm of the box-lever would assume should the upward movement of the box-rod be arrested.

Similar letters of reference indicate corresponding parts in the several figures.

The object of this invention is to improve the box-lever of a power-loom, for weaving fancy fabrics, by providing such lever with a jointed extension, which is adapted for carrying the weight used to counterbalance the weight of the shuttle-boxes and their rod, and which is also adapted for allowing the box-lever to move independently of its extension, should the shuttle-boxes be arrested in their upward movement, as will be hereinafter explained.

On the 12th day of May, 1863, Letters Patent of the United States were granted to BARTON H. JENKS and John Shinn, and assigned to myself, for an improvement on box-levers for power-looms, which levers were provided with jointed extensions, which would yield and prevent breakage of the shuttle boxes, or other parts of the box-motion, in case the picker or shuttles should be caught in the shelves of the boxes in the act of rising.

In the practical operation of levers thus constructed, it is found that the weight which must be employed to counterbalance the weight of the shuttle-boxes and their rod, will produce a trembling and irregular motion, owing in part to the speed which the lever receives, and the inertia of the counterbalancing weight.

I do not, therefore, claim under this petition the broad idea of a yielding extension to a box-lever.

To enable others skilled in the art to understand my invention, I will describe its construction and operation.

In the accompanying drawings—

D represents a box-lever, which is pivoted to one side of the frame A, at a, so as to vibrate freely in a vertical plane.

D' represents an extension of the lever D, which is pivoted, at b, to that end of this lever nearest the box-rod C, by means of a rule-joint, s, and which extends forward in the plane of lever D, beneath a shoulder, h, on the said rod, so as to afford a support therefor.

The extension D' is held in its position in line with the box-lever, as shown in fig. 1, by means of a weight, B, which is applied on the long arm, D'', of this extension, which arm may be made of any desired length, and should be carried back of the fulcrum a, so that

the weight B will counterbalance the weight of the shuttle-boxes, the shuttles, and the box-rod C.

This arm D'' is a part of the extension D', and is curved outward, and extended backward, as shown in fig. 2.

The weight B should not only counterbalance the load on the extension D', but it should be sufficient to keep this extension in line with the box-lever under all ordinary circumstances.

The box-rod C is arranged to move up and down vertically in the guides g g', and is supported upon the extension D' by the adjustable shoulder h, in the usual well-known manner.

Upon its upper end this rod carries the shuttle-boxes, not shown in the drawings, which may be controlled in their vertical movements by cams and a pattern chain or studded cylinder, arranged to operate upon the rear arm of lever D, in the usual well-known manner, as in any suitable manner.

It frequently happens, during the operation of the shuttle-boxes and their accessories, that the pickers or the shuttles will lodge or be caught in such manner as to resist the upward movement of the boxes, and unless provision is made which will allow the box-lever to work freely under these circumstances, the boxes, or box-motion, or both, will be injured.

In the Letters Patent numbered 38,534, above referred to, the box-lever is provided with an elastic extension, upon which the box-rod rests, which extension will yield should the upward thrust of the box-rod be resisted, as above stated, and prevent breakage or derangement of the parts.

It will be seen that I still employ a jointed yielding extension of the box-lever, but instead of using a spring to hold up or stiffen the joint of this extension, and applying a counterbalancing weight on that end of the box-lever which is acted upon the cams, I employ the weight B to stiffen the rule-joint at b s, and apply this weight upon an arm, D'', so that it will also serve to counterbalance the load upon said extension D'.

When the box-lever is thus constructed, or provided with a counterbalancing weight and yielding extension, the objections attending the elastic extension, above alluded to, will be obviated, and should the shuttle-boxes be arrested by the pickers or the shuttles during the operation of the loom, the extension D' will yield, as shown in fig. 3, and prevent injury or derangement to the parts.

Having described my invention,

What I claim as new, and desire to secure by Letters Patent, is—

The box-lever D, or its equivalent, provided with the yielding extension D', acted upon by the counterbalancing weight B, applied upon the arms D'' of said extension, substantially as and for the purposes described.

BARTON H. JENKS.
